UNITED STATES PATENT OFFICE.

LAUDA E. LIGHTNER AND CHESTER BRADFORD, OF INDIANAPOLIS,
INDIANA.

TYPE-WRITER DESK.

SPECIFICATION forming part of Letters Patent No. 783,875, dated February 28, 1905.

Application filed July 9, 1903. Serial No. 164,928.

To all whom it may concern:

Be it known that we, LAUDA E. LIGHTNER and CHESTER BRADFORD, citizens of the United States, residing at Indianapolis, in the county 5 of Marion and State of Indiana, have invented certain new and useful Improvements in Type-Writer Desks, of which the following is a specification.

The object of our said invention is to produce a type-writer desk in which the type-writer may be moved from operative to folded-up position and by the same act the working table of the desk raised from the level required for type-writing purposes to the ordinary desk-level and there held until the type-writer is thrown back to position for use, when the said table will sink to its former position:

A desk embodying our said invention will be first fully described and the novel features 20 thereof then pointed out in the claims.

Referring to the accompanying drawings, which are made a part hereof, and on which similar reference characters indicate similar parts, Figure 1 is a front elevation of a desk 25 embodying said invention; Fig. 2, a transverse vertical sectional view of the same as seen when looking in the direction indicated by the arrows from the dotted line 2.2 in Fig. 1, and Fig. 3 an under side plan view of so much of 30 the structure as is involved in our invention and immediately adjacent parts as seen when looking upwardly from the dotted line 3.3 in Fig. 1.

We have shown our invention as applied to 35 the variety of desks denominated "roll-top" desks. Within the walls 10 of such a desk we place the table 11. This table is capable of a position-shifting movement, whereby it is adapted to travel up and down between the 40 rest-brackets 12 and the stops 13. When the table is in its lower position upon the rest-brackets 12, it is at the height which is convenient for type-writing purposes. When it is forced upwardly against the stops 13, it is 45 at the usual or convenient height of desk-tops or tables generally. The type-writer 14 is secured to suitable lever-like supports 15, which are pivoted at 16 to brackets 18 or to suitable adjacent portions of the desk struc-

ture, and the type-writer can be swung from 50 the operative position (shown by full lines in Fig. 2) to the folded-up position (shown by dotted lines therein) on said pivoted supports. When in operative position, said type-writer rests upon the table 11. When in folded-up 55 position, it should rest against suitable stops 19 on adjacent portions of the desk structure. At the rear end the lever-arms 16 are connected by pivots 20 to links 21, which are in turn, by means of pivots 22, connected to levers 23, and these levers in turn are connected by pivots 24 to brackets 25, which are attached to the under side of table 11.

The operation will be easily understood by a comparison of the full lines and the dotted 65 lines in Fig. 2. When the type-writer is raised, it operates, through the supports 15, the links 21, and the levers 23, to at the same time raise the table 11. When the type-writer reaches the position shown by the dotted lines, 70 the table has by the same movement been raised to ordinary desk-top level.

The type-writer when raised is moved into a chamber formed to receive it and if the raising is more than temporary can be concealed 75 by means of an inner roll-curtain 31, which runs just within the walls of said chamber and just beneath the ordinary desk-roll curtain 32 or if the height of the desk permits beneath upper compartments or pigeonholes 80 of said desk below said ordinary roll-curtain. The inner-roll curtain 31 completely protects the type-writer from dust while the desk is being used for ordinary purposes and also greatly improves the appearance of the device 85 during such use. The plan of placing the machine above the surface of the desk instead of below permits the operative to be occupied at the same desk upon other of the various classes of work and for any length of time 90 without being placed in a cramped position by the drop-board, which is present in those desks in which the machine drops below the surface and which falls diagonally across the knees and precludes an easy and comfortable 95 position at the desk when handwork is being performed.

The interior arrangement of the desk may be

anything desired. It should for convenience contain shelves, pigeonholes, and drawers for the reception of stationery, books, &c. A convenient arrangement (so far as these matters are concerned) is illustrated in Fig. 1 of the drawings.

Having thus fully described our said invention, what we claim as new, and desire to secure by Letters Patent, is—

- 10 1. In a type-writer desk, the combination, with a main casing, of a movable table forming part of the writing-surface thereof, a pair of levers pivotally mounted on said casing and pivotally carrying said table, a pivoted type-
writer support mounted on the casing, and intermediate connections connecting said pair of levers and said pivoted type-writer support, whereby as the table is lowered the type-writer is deposited upon said table and as said
20 table is raised the type-writer is removed therefrom.
- 25 2. In a type-writer desk, the combination, with the main casing, of a table forming part of the writing-surface thereof, a pair of levers pivotally mounted on the casing, a pivoted support carried by said levers and carrying said table, a pivoted type-writer support mounted on the casing, and intermediate connections connecting said pair of levers and the
30 type-writer support whereby the two will swing simultaneously and the type-writer be brought into operative position when the table is lowered, for the purpose set forth.
- 35 3. In a type-writer desk, the combination,

with the main casing, of a table having a vertical movement and adapted to support the type-writer when in its lower position and to serve as a desk-top when in its upper position, a type-writer support pivoted on the main casing and extending over said table when in position for type-writing use, and intermediate connections between said type-writer support and said table whereby the swinging of the type-writer support will produce simultaneous vertical movement of the table.

4. In a type-writer desk, the combination, with the main casing having a chamber formed in its rear portion above the level of the table to receive a type-writer when not in use, a vertically-moving table forming part of the writing-surface of said desk, a pivoted support for the type-writer mounted on the casing and arranged to be swung into and out of said chamber, and intermediate connections between said type-writer support and the table whereby the table will be lowered when the type-writer support is swung out of said chamber and raised when the support is swung into said chamber.

In witness whereof we have hereunto set our hands and seals, at Indianapolis, Indiana, this 15th day of June, A. D. 1903.
